UNITED STATES PATENT OFFICE.

WILLIAM H. APPLEBY, OF WINDSOR, ONTARIO, CANADA.

RADIATOR VENTILATOR AND CAP.

1,344,609.

Specification of Letters Patent. Patented June 29, 1920.

Application filed May 19, 1919. Serial No. 298,341.

To all whom it may concern:

Be it known that I, WILLIAM H. APPLEBY, a subject of the King of Great Britain, residing at Windsor, in the county of Essex, Province of Ontario, Canada, have invented certain new and useful Improvements in Radiator Ventilators and Caps, of which the following is a specification, reference being had therein to the accompanying drawings.

This invention relates to a radiator ventilator and cap, and my invention aims to furnish a radiator with a novel air intake member which will produce an inrush of cold air into the upper portion of the radiator during the operation of an automobile, truck and motor driven vehicle or air craft, to lower the temperature of the water therein and thus increase the efficiency of the water as a cooling agent for the engine or power plant of the automobile, particularly in the summer time. It is in this connection that the device is provided with a cap or disk that may be easily and quickly installed to close the filling opening of the radiator during the winter time, and in either instance the device does not interfere with the filling of the radiator in the usual manner, as it is only necessary to remove the ventilator or cap.

My invention further aims to provide a device of the above class which may be more or less ornamental, and provision is made to prevent the splashing of the water or cooling agent from the radiator and at the same time deflect air therein.

My invention further aims to provide a simple, durable and inexpensive device that will be hereinafter specifically described and then claimed, and reference will now be had to the drawing, wherein

Figure 1 is a perspective view of a portion of the radiator provided with a ventilating device in accordance with my invention;

Fig. 2 is a vertical sectional view of the same; and

Fig. 3 is a similar view showing a cap or disk installed, particularly during the winter time.

In the drawing, the reference numeral 1 denotes a portion of a conventional form of radiator or cooling apparatus forming part of a well known automobile and the cooling principle involved in connection with an engine or motor is commonly known as the

thermo-siphon system, wherein the hot water seeks a higher level in the radiator or apparatus than the cold water, and when the water reaches a predetermined temperature circulation commences through the radiator or cooling apparatus. The top of the radiator has an opening 2 surrounded by a filling connection 3 which is somewhat frusto-conical shape and has its upper end terminating in an interiorly screwthreaded socket 4, which ordinarily receives a cap, plug or other closure member.

My device comprises a tube 5 having the lower end thereof enlarged and exteriorly screwthreaded, as at 6, so that it may be screwed into the socket 4 and an annular flange 7 of said tube limits the screwing in movement of the lower end of the tube relative to the socket 4, providing a small space 75 so that a cap or disk 9 may be seated in the socket 4 and retained therein by the tube 5 to close the connection 3, particularly in the winter time. The cap or disk 9 may be made of metal or any suitable material and provides a closure for the filling connection 3 that may be removed by unscrewing the tube 5.

The upper end of the tube 5 is somewhat funnel shaped by being formed with a substantially semi-cylindrical air intake head 10 having a front open side 11 which faces forward and is adapted to receive air, particularly when an automobile is in motion. The air entering the head 10 impinges 90 against the rounded walls of said head and is deflected downwardly through the tube 5 into the top of the radiator 1, where the cold air strikes the water or cooling agent in the radiator and reduces the temperature 95 of the same.

To facilitate the deflection of air by the head 10, the open side 11 of said head is provided with a plurality of transverse equally spaced deflectors 12, said deflectors being 100 disposed in parallelism and each at such an angle that air is deflected downwardly into the tube 5. The outer edges of the deflectors 12 form bars transversely of the front open side of the head 10 and prevent large bodies 105 of solid matter being placed in said head. Any rain that may enter the spaces between the deflectors is carried downwardly through the tube 5 without contacting with the concave walls of the head 10, and with the ventilating device made of aluminum or a metal treated so as not to corrode there

- is no danger of the general appearance of the ventilating device detracting from the appearance of the radiator or accessories of the automobile. It is in this connection 5 that the device may be finished to conform to metallic fittings of the automobile, and the shape of the device permits of its being easily manipulated when it is desired to detach the device to fill the radiator.
- 10 A screen 14, as a piece of wire gauze, may be placed in the radiator filling connection 3 and held in place by the tube 5, said screen arresting dust and other foreign matter and also serving as an anti-splash member for 15 the contents of the radiator.
- I attach considerable importance to the somewhat funnel shape of the device as sufficient air will be gathered in at the open side or end thereof to insure a cooling effect on 20 the water or cooling agent within the radiator. It is furthermore possible to set the ventilating device so as to face the wind, when an automobile is inactive, and thus permit of a draft of air cooling the contents 25 of the radiator, particularly when the engine of the automobile is idling. The de-

vice may also be connected to the water jacket of an exposed engine or to any body to which air may be admitted for cooling purposes.

One embodiment of my invention has been 30 illustrated, but it is to be understood that the structural elements are susceptible to such changes as fall within the scope of the appended claim.

35 What I claim is:—

The combination with a filling connection 40 of a radiator, the filling connection having an annular seat, of a funnel shaped air intake device having its lower end connected to the filling connection of said radiator, and a detachable cap on the seat of the filling connection of said radiator and retained thereon by the lower end of said device.

45 In testimony whereof I affix my signature in the presence of two witnesses.

WILLIAM H. APPLEBY.

Witnesses:

KARL H. BUTLER,
ANNA M. DORR.
